DEVICE FOR RAPIDLY DETERMINING THE
FINENESS OF FIBERSJohn I. Hardy, Washington, D. C., dedicated to
the free use of the Public

Application October 29, 1932, Serial No. 640,227

2 Claims. (Cl. 72—51)

(Granted under the act of March 3, 1883, as
amended April 30, 1928; 370 O. G. 757)

This application is made under the act approved March 3, 1883, as amended by the Act of April 30, 1928; and the invention herein described, if patented, may be manufactured and used by or for the government for governmental purposes without the payment to me of any royalty thereon.

I hereby dedicate the invention herein described to the free use of the public, in the territory of the United States, to take effect upon the granting of a patent to me.

This invention relates to a device having a fiber slot for use in rapidly determining the fineness of wool and other fibers.

The methods ordinarily used in measuring the fineness of individual fibers involve the use of microscopes and micrometer calipers. The operation of such equipment is slow and expensive and not adapted to wide application. One old method recently improved involves the actual measuring of the mean cross-sectional area of 100 fibers. In another method the fineness is obtained by comparing the light defraction values for wool with that of fibers of known fineness. Neither of these methods are sufficiently simple in operation to make them wide in their application. The fiber slot device is so simple and efficient in its operation that it offers possibilities of being widely used. Those not expert in judging wool are afforded a ready means of obtaining the degree of wool fineness. Those who have some knowledge of judging wool will find it helpful in testing their judging ability and it is especially helpful as an aid to judgment in the selection of standard samples. The application of this device does not limit itself to wool alone for it is a valuable aid in the determination of the mean diameter of other animal as well as many vegetable and artificial fibers.

My process consists of ascertaining the number of fibers which will fill a previously determined space. I attain this object by the mechanical device illustrated in the accompanying drawing in which Figure 1 is a side elevation of the entire device; Figure 2 is an end elevation thereof; Figure 3 is a detailed view of the knife attachment and Figure 4 is a detailed view of the knife adjustment mechanism.

Similar numerals refer to similar parts throughout the different views.

The apparatus consists principally of four parts: a hand-operated knife and holder assembly 1; a fiber holder 2; an upright supporting post 3; and a base 4.

The knife and holder assembly 1 consists of

two plates 10, 11 held together at one end, hereinafter referred to as the handle end, by a bolt 5 and two taper pins 6, 6. In the other end are three holes 7, 8, 9 arranged horizontally and corresponding to the opening or openings found in a safety razor blade. Between these two plates at the handle end, is placed a thin piece of metal 32 which slightly separates the two plates, leaving space for the insertion of a safety razor blade 12 at the other end. Into this space a safety razor blade 12 having three holes or a longitudinal slot, is placed. Through the hole nearest the handle end is inserted a snug-fitting bolt 13, which holds the blade in position. Through the holes in the other end of the knife and holder assembly is inserted a loose-fitting bolt 14, which also passes through the opposite end of the razor blade. This permits a slight up-and-down movement of the blade at the end farthest from the handle (Figure 3). This motion is actuated by a bolt 15 having an eccentric bearing 16 and a knurled head 17. This bolt passes through the center hole 8. The knurled head is graduated in half mm. (see 18, Figure 4) in order to make it possible to indicate the exact position of the blade at any time. Both of the plates 10, 11 are cut away at the lower edge 19, exposing the razor blade for one and one-quarter inches of its length toward the handle end, tapering uniformly from two mm. at the handle end to three mm. at the other end, providing space for manipulating the blade. It is necessary that the opening at the end of the greatest depth provide a right angled shoulder. Beyond the cut away portion of the holder one side has a ruler edge, graduated in half mm. units 20. This edge is tapered slightly from the opening to the end of the holder. The purpose of this graduation is to facilitate the setting of the blade. For example, if it is found from a preliminary cutting that the blade 12 is set either too high or too low, that is to say, the blade is leaving an incorrect number of uncut fibers in the fiber slot 21 to fill a given space, as hereinafter discussed, the degree of change to be made in the position of the blade may be estimated closely by the graduations on the ruler edge. The entire knife and holder assembly, although shown in place in the cutting slot 27 of the fiber holder 2, is a separate unit and in no way attached to the fiber holder.

The fiber holder 2 is constructed of two plates 22, 23. A metal shim 24 is placed between these two plates at the lower end and they are bolted together with two bolts 25, 25. This forms an

opening 27 between the two plates 22, 23 at the upper end, permitting the entrance of the razor blade 12. This opening is called the cutting slot. The fiber holder is attached to the supporting post 3 by a bolt 26. Another very narrow slot, called the fiber slot 21, slightly wedge shaped, except at the extreme lower end where it forms an acute angle, is cut into the top end of the two plates, forming the fiber holder. This opening 10 is at right angles to the cutting slot. The object to be accomplished is to have the bottom of the slot slightly deeper than the cutting depth of the razor when in operation.

The supporting post 3 is composed of a rod 15 slotted at the top to permit attachment of the fiber holder 2 and threaded to the base 4. Two, ten gram weights 28 28, a supply of thread 29 and ordinary adhesive tape 30 complete the equipment as shown in Figure 2.

20 To operate the device the ten gram weights are attached by means of adhesive tape and the thread to a lock of wool 31 or other fiber sufficiently large to fill the fiber slot above the greatest depth reached by the razor blade. The lock is then placed in the fiber slot 21 and is pulled gently by the fingers to the bottom of the fiber slot, the weights hanging on either side of the device. The razor blade 12, previously adjusted to the desired position, is then inserted in the cutting slot 27 at the edge nearest the handle end. The knife and holder assembly is then held at right angle to the fiber holder and drawn gently through the cutting slot and across the fibers throughout the exposed length of the blade. The purpose of this operation is to fill a specific space with fibers in order that all fibers in excess of those needed to fill the space will be cut by the knife. The knife is removed and the lock of wool or other fiber withdrawn from the holder 40 by grasping it close to the fiber holder with the

thumb and forefinger of the right hand and with the other hand cutting the lock free from the opposite end. The cut fibers from that end of the lock are removed by the thumb and forefinger of the left hand while the right hand still firmly grasps the other end. Then the uncut fibers are held firmly by the thumb and forefinger of the left hand and the process is repeated in freeing the other end from uncut fibers. The uncut fibers still grasped between the thumb and forefinger of the left hand are then counted by the use of tweezers. The operation is facilitated by the use of a black background. There is a direct correlation between the number of fibers occupying the slot and remaining uncut by this operation and the fineness of the fiber. If too large a lock of wool is used its size may be reduced by making a preliminary cut.

Having fully disclosed by discovery I claim as my invention:

1. A device for use in determining the fineness of fibers which comprises a base, a post rigidly attached in a vertical position to said base, a member rigidly attached to and extending upwardly from the upper end of said post and having two vertical slots in the upper end thereof at right angles to each other, a knife holder, a knife associated with said holder and means to adjust said knife to permit its insertion in one of said slots to a predetermined depth. 100

2. In a device for use in the determination of the fineness of fibers, a fiber holder comprising a member having two vertical slots in the upper end thereof at right angles to each other, means to sustain said member in a working position, a knife and holder assembly and means to adjust the position of the knife in the holder to permit its insertion in one of said slots to a predetermined depth. 110
